UNITED STATES PATENT OFFICE.

ROWLAND WILLIAM EASTON, OF LONDON, ENGLAND, ASSIGNOR OF ONE-HALF TO JOHN LESLIE CLOUDSLEY AND OSWALD CLOUDSLEY, BOTH OF LONDON, ENGLAND.

SCREW CONVEYER.

Application filed June 2, 1920. Serial No. 385,952.

(GRANTED UNDER THE PROVISIONS OF THE ACT OF MARCH 3, 1921. 41 STAT. L., 1313.)

To all whom it may concern:

Be it known that I, Rowland William Easton, a subject of the King of England, residing at London, England, have invented 5 certain new and useful Improvements in Screw Conveyers (for which I have filed applications in France, Patent 496,424, dated Mar. 3, 1919; Spain, Patent 69,264, dated Apr. 29, 1919; India, Patent 4,258, dated Mar. 3, 1919; Great Britain, Patent 109,663 (13603/16), filed Sep. 25, 1916; Great Britain, Patent 116,873 (45251/18), filed Mar. 14, 1918; Belgium, application H356, filed Mar. 7, 1919; Australia, application 10623, filed Mar. 31, 1919; South Africa, Patent 193/19, dated Mar. 19, 1919; and Canada, application 227,613, filed Mar. 12, 1919), of which the following is a specification.

20 This invention relates to improvements in screw conveyers for lifting liquids and for use in retorts, coke ovens and the like. The conveyer may be used for conveying, forcing or pumping gaseous, liquid, viscous or 25 granular materials. Such materials may be treated, as, for example, by heat, while in the conveyer.

According to the invention, in a screw conveyer for lifting liquids and for use in a 30 retort, coke oven or the like, there are provided two intermeshing screws of similar pitch which are of the same hand (either both right-handed or both left-handed) and which rotate in the same sense in close 35 proximity to one another, and a casing which closely surrounds both conveyers.

According to a further feature of the invention in a continuous retort for the distillation of carbonaceous material or the like, 40 there is combined with a casing of metal or refractory material arranged in a furnace and having means for supply and discharge and an outlet conduit for distillate, two intermeshing screws of similar pitch closely housed in said casing and arranged and operated as above described.

In the accompanying drawings—

Figure 1 is a sectional view of a portion of a conveyer constructed according to this 50 invention, taken along the axis of the screws;

Figure 2 is a cross-sectional view; Figure 3 is a vertical longitudinal section of a retort according to this invention; Figure 4 is a plan in part-section; 55 Figure 5 is a cross-section, and Figure 6 is a sectional plan of another construction.

Referring to Figures 1 and 2, two screws A, A, each having, as shown, a coarse 60 deeply-cut thread of the same hand and pitch in both screws, are arranged side by side with their threads intermeshing. A casing B surrounds the screws and, as shown, is made to fit as closely as possible 65 to their combined cross-sectional shape. Means (not illustrated) are provided for rotating both the screws in the same direction.

The threads of the screws A, A, are made 70 alike and complementary, so that the one fits closely into the other, providing a continuous line of contact between them, extending from end to end of the conveyer. By this means material being conveyed is 75 prevented from slipping back along the threads and positively caused to advance as the screws rotate.

This conveyer may be used for a variety 80 of purposes, including the lifting or conveying of liquids, viscous materials, or liquids having solids in suspension therein, or powdered, granular or lumpy materials. For example, coal, shale, peat, sewage, china 85 clay, gravel, sand, crushed rock and ore and the like, may be conveyed. Owing to the positive action a high speed is unnecessary, and moreover the apparatus may be employed for forcing material into dies, 90 moulds or receptacles, as in sausage machines, briquetting machines, and the like, and in the manufacture of soft metal tubing. In the last case the material is forced through dies by the apparatus in a continuous automatic process. 95

In the treatment of disintegrated material suitable binding agents can be added during their passage through the apparatus to dies or moulds.

Heat may be applied to the material while 100 in the apparatus, either externally or by means of steam, and to allow for alteration

in bulk or other physical changes in the material during its passage through the apparatus, the screws may be made to taper.

In all these applications of the invention a great advantage arises from the fact that the surfaces of the two screws at the point of meshing are moving in opposite directions and thus they keep each other clean. Moreover there are no valves, gears, or other objectionable intricately-shaped objects within the conveyer to collect dirt.

Referring to Figures 3-5, the retort for the distillation of material to be treated consists of a casing A which surrounds and for the most part fits closely against two screw conveyers B, B, arranged side by side, and each having a deep coarse-pitch thread of the same hand and pitch, so that they intermesh together. The screws B, B, are rotated in the same direction as one another by gearing C outside the retort.

At the inlet end of the retort is a hopper D provided with a gas-tight revolving door I operated by a worm gear H. The residue of the treated material falls from the other end of the retort into a hopper E, provided with a revolving door for the exit of the residue.

The casing A is provided above and between the screws B, for almost its whole length, with an elongated enlargement G, which constitutes a chamber for collecting and drawing off the distilled gas, which is afterwards led away through the pipe F. The lower half of the casing however is made to fit the screws quite closely so that the retort may not have any pockets or portions untraversed by the screws, wherein material might get clogged.

The retort as above described and illustrated is intended to be built into a suitable furnace setting, and may be set horizontal, vertical or inclined, as found suitable for the purpose in hand. The casing may be of metal, fireclay or firebrick.

In treating coal and other materials which increase in size during treatment, the screws B, B, and retort A, are preferably made to enlarge slightly towards the rear or hottest portion of the furnace to allow for the expansion of the material.

Figure 6 shows a construction of coke oven wherein the screws B do not extend through the whole length of the retort, but merely feed the coal into the enlarged main portion K, through which it is then pressed as a solid mass by the fresh material entering by the screws. Suitable gas and coke exits are of course provided. This oven also must of

course be set in a suitable brickwork furnace. The screws, however, are outside the furnace, away from the heat.

If desired, more than two screws may be arranged side by side in the manner described.

What I claim as my invention and desire to secure by Letters Patent is:—

1. The combination, with two endless male screws of the same hand and pitch arranged lengthwise side by side meshing one with the other, of a retort body having an inlet for material to be distilled at one end, an outlet for residue at the other end, and an enlarged middle portion that has an outlet for gases, the inlet end of which body lying on opposite sides of a plane including the axes of the screws is symmetrical and extends completely around and closely fits the periphery of the intermeshing screws as viewed in cross section, and means arranged to rotate each of said screws in the same direction as the other whereby the engaging portions move in opposite directions, substantially as described.

2. The combination, with two endless male screws of the same hand and pitch arranged lengthwise side by side meshing one with the other, of a retort body whereof two end portions lying on opposite sides of a plane including the axes of the screws is symmetrical and extend each completely around and closely fit the periphery of the intermeshing screws as viewed in cross section, which retort body has an enlarged middle portion that provides a space for gases above said screws and has an outlet, which end portions are provided one with an inlet for material to be distilled, and the other with an outlet for residue, and means arranged to rotate each of said screws in the same direction as the other whereby the engaging portions move in opposite directions, substantially as described.

3. In a retort, a retort body having restricted inlet and outlet portions of substantially the same size and an enlarged intermediate portion, and means for positively forcing material through said body, substantially as described.

4. In a retort, a retort body having restricted inlet and outlet portions of substantially the same size and an enlarged intermediate body, and rotating means closely fitting the ends of the body for positively forcing material therethrough, substantially as described.

In testimony whereof I affix my signature.
ROWLAND WILLIAM EASTON.
